US0D1043622S

(12) **United States Design Patent** (10) **Patent No.:** **US D1,043,622 S**
(45) **Date of Patent:** **** Sep. 24, 2024**

(54) **WIRELESS EARPHONES AND CASE**

(71) Applicant: **Shenzhen Ego Ark Technology Co., LTD.**, Shenzhen (CN)

(72) Inventor: **Hongping Huang**, Shenzhen (CN)

(73) Assignee: **Shenzhen Ego Ark Technology Co., LTD.**, Shenzhen (CN)

(**) Term: **15 Years**

(21) Appl. No.: **29/873,253**

(22) Filed: **Mar. 28, 2023**

(51) LOC (14) Cl. **14-01**

(52) U.S. Cl.

USPC **D14/223; D3/274**

(57) **CLAIM**

The ornamental design for wireless earphones and case, as shown and described.

DESCRIPTION

FIG. 1 is a top perspective view of a case of the wireless earphones and case, showing my new design, the case is shown separately for ease of illustration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top perspective view of wireless earphones of the wireless earphones and case thereof, shown separately for ease of illustration;

FIG. 9 is a front view thereof;

FIG. 10 is a rear view thereof;

FIG. 11 is a left side elevational view thereof;

FIG. 12 is a right side elevational view thereof;

FIG. 13 is a top view thereof;

FIG. 14 is a bottom view thereof; and,

FIG. 15 is a top view of the wireless earphones and case in an open position thereof.

The broken lines in the drawings illustrate portions of the wireless earphones and case, which form no part of the claimed design.

1 Claim, 15 Drawing Sheets
